[57] CLAIM

The ornamental design for a grommet with pivoting tab, as shown and described.

DESCRIPTION

FIG. 1 is a perspective view of the grommet with pivoting tab of my new design showing the tab in the closed position;

FIG. 2 is a front elevational view thereof;

FIG. 3 is a back elevational view thereof;

FIG. 4 is a side elevational view thereof, both sides being the same;

FIG. 5 is a top plan view thereof;

FIG. 6 is a bottom view thereof; and,

FIG. 7 is a reduced perspective view thereof with the tab pivoted to the open position.

FIG. 1

FIG. 2

FIG. 3

FIG. 4

FIG. 5

FIG. 6

FIG. 7
